COMPOSITE RADIO FREQUENCY
INDUCTANCEJulius W. Mann and George F. Russell,
Tacoma, Wash.

Application July 31, 1944, Serial No. 547,440

4 Claims. (Cl. 175—359)

1

The present invention relates to improvements in a composite radio frequency inductance, and it consists of the combinations, constructions and arrangements hereinafter described and claimed.

This application is a continuation-in-part of our copending application for a Composite radio frequency inductance, Serial No. 451,064, filed July 15, 1942, now abandoned.

An object of our invention is to provide a composite radio frequency inductance that is especially designed to be used in our Single standing wave radio circuit copending application, Serial No. 510,566, filed November 16, 1943. In the Radio circuit case, we set forth a particular arrangement of a plate, grid and output circuits which the current antinodal positions of all three circuits to coincide at a common center point in the composite inductance. The physical means for accomplishing this is illustrated, described and claimed in the present case.

The advantage of causing the three circuits to have their current antinodal positions at a common center point on the composite inductance is to permit the radio circuit to be tuned throughout a wide range of frequencies without a resulting loss in stability which is many times the case where the current antinodal positions of the three circuits are not held at a common point.

The plate circuit has its coil physically separated from the coil of the combined grid output circuit by air or other insulating means. The number of turns or loops of the grid output circuit coil may be changed in accordance with the operating wave lengths of the circuit. At high frequencies the coil may be only a portion of one turn, while at lower frequencies the coil may have many turns. The composite radio frequency inductance is simple in construction and provides an effective means for bringing the coupling current antinodal positions of all the circuits to a common point at the center of the composite inductance. The two components of the inductance may extend in a straight line rather than be coiled.

Other objects and advantages will appear in the following specification, and the novel features of the device will be particularly pointed out in the appended claims.

Our invention is illustrated in the accompanying drawings forming a part of this application, in which:

Figure 1 is a perspective view of the composite radio frequency inductance shown diagrammatically connected to a radio circuit;

Figure 2 is a wiring diagram of one type of

radio circuit in which our invention may be used;

Figure 3 is a section along the line 3—3 of Figure 1;

Figure 4 shows the two components of the inductance straightened out and separated by an air gap; and

Figure 5 illustrates another circuit modification using straight line inductances separated by air.

10 In carrying out our invention we will first describe the radio circuit in which the composite radio frequency inductance is used and then the construction of the inductance itself. The radio circuit shown in Figure 2 is the same as Figure 1 of our copending application, Serial No. 510,566. A brief description will be given. The plate circuit is indicated generally at A and comprises plates 1 in radio tubes T1 and T2, an inductance coil L1, and a variable condenser 2 which is shunted across the inductance coil. The plate leads 3 are crossed.

20 The grid circuit is indicated generally at B and comprises grids 4, protective condensers 5, and resistances 6. An output, pick-up or work circuit, indicated generally at C, has an inductance coil L2 which is inductively coupled to the coil L1. The circuit C also has inductance extremities 7 and 8 with adjustable leads 9 and 10 connected to plates 11 and 12 between which the work W is placed. It will be noted that the leads 13 and 14 of the grid circuit B are adjustably connected to the extremities 7 and 8 so that the grid and output circuits are physically the same for a portion of their lengths.

30 35 The inductance coils L1 and L2 are indicated diagrammatically in the radio circuit of Figure 2. In Figures 1 and 3 the physical construction of the two coils is shown. The combined grid output circuit coil L2 comprises a tube 15 that has only one half a loop formed therein. As already stated, the tube could have one or more loops formed therein according to the frequency of radio circuit used and the tube may be solid if desired. The portion of the tube 15 that is formed into one half a loop is covered by an insulating sleeve of rubber 16. Around the rubber sleeve we mount a tubular member 17 that has a half turn formed therein. The coil L1 has a number of loops and has its mid portion physically connected to the tube 15 at 18. The physical connection is such that a center point K of the coil L1 will be at the center of the tube 17 which in turn will be at the center of the half loop of the coil L2. The midpoint K of the coil L2 will

40 45 50 55 be entirely enclosed by the rubber sleeve 16 which

in turn is entirely enclosed by the tube 17. In this way the center of the two coils are placed in concentric relation with the sleeve 6 insulating the two centers from each other. Figures 3 show the central portion of tube 15 which is formed into the half loop L2 and further illustrates the insulating sleeve 16 and the external tube 17. The wire 20 leading from the center of the tube 17 connects with the B+ source of current.

As stated above mid point K in the inductance shown in Figure 1 of the drawings is entirely enclosed by rubber sleeve 16, which in turn is entirely enclosed by tube 17. Let it be pointed out clearly in that connection that a center tap from the coil L2 running inside of the outer tube 17 may be taken out at point K without disturbing the meaning of this specification. A center connection on L2 could be either for inserting resistance to control oscillations or to ground same through a grid resistance, thereby changing the grid return system shown in Figure 2.

The inductances L1 and L2 are designed to have a minimum capacitive coupling between the coils at their voltage antinodes, or in other words, where the voltage is high relative to the center point of the respective inductances (coupling current antinodes). This is accomplished by the grid output circuit coil, L2, following the plate tank coil, L1, to only a limited physical distance and bringing the leads away from the capacitive relationship so as to reduce the effect of such capacitive coupling. The closest possible coupling at the coupling current antinodes most nearly approaches the ideal position of relationship for the transfer of energy and this is shown in Figure 1. The coupling current antinodal position for all three circuits is shown at K in this figure. The same variable capacity used for tuning in a close coupling will cover a range over twice that covered by the same variable capacity with a loose coupling between the inductances L1 and L2. The closer the two coils L1 and L2 approach 100% mutual inductive coupling, the greater becomes the range covered by a given variable tuning device in the dominant circuit.

We have shown a self-excited oscillator in Figure 2 where the plate tank circuit is the dominant one. We do not wish to be confined to any one of the three circuits as being the dominant one. In the case of a receiver, the grid circuit may be the dominant one and then the plate circuit can have a coil which will be concentric to the grid circuit coil for a portion of its distance. The wire or tube forming the coil for the grid circuit may be placed within a tubular wire or outside of the wire coil constituting the plate inductance. The distance that the coil of the dominant circuit runs concentric to the coil of the other circuit or circuits with which it is inductively coupled is based on the operating wave lengths of the circuit and/or the constants thereof. As already stated, at high frequencies the coil may consist of only a portion of a turn or loop while at lower frequencies it may comprise many turns or loops.

In Figures 4 and 5 we show a modified form of the composite radio frequency inductance. In both figures the inductance is composed of two concentric tubes with air as the insulator between the tubes instead of rubber or other artificial insulation. Figure 4 illustrates an inner tube inductance, L3 as being connected in the grid circuit B and the work circuit C. The grid circuit B has leads 13 and 14 adjustably connected to the wires 7 and 8 of the work circuit by taps 21 and 22.

The outer concentric tube constitutes an in-

ductance L4 and this tube is insulated from the inner tube L3 by air and forms a part of the plate circuit A. The B+ current is connected to the tube L4 at K while the center of the tube L3 is tapped at K' by a lead 23 that connects with a resistance 24 and the resistance is grounded at 25. The plates 1 of the tubes T1 and T2 are interconnected by a variable condenser 2. It will be noted from Figure 4 that the grid blocking condensers 5 shown in Figure 1, are not used in the radio circuit disclosed in Figure 4. Both inductances L3 and L4 are center tapped.

The operation of this form of the invention is the same as that shown in Figure 2. The important relationship of the inductances to the various circuits is that the mutual inductance of the two component parts L3 and L4 extend for equal distances on either side of their coinciding center points K and K'. By this we mean that the two inductances extend coaxially, as set forth in Figure 3 and their coaxial portions are small in proportion to their total respective lengths. The coaxial member L3 constitutes the center portion of the grid circuit and the coaxial portion L4 constitutes the central portion of the plate circuit.

The electrostatic strain under conditions of radio frequency energy are such as to puncture the most defective part of any insulating means placed between the two concentric members L3 and L4 of the mutual inductance. Once this insulating means is punctured, if it is made of rubber or other insulating material, nothing can be done but remove it and substitute a new one. If air is used as insulation as shown in Figure 4, and an arc should occur between the inductances, the air is self-healing and after the arc is extinguished the inductance can be used as before without any change. For this reason air is shown as the insulation used in Figure 4.

It makes little difference whether the inductance is shaped like a coil, as in Figure 1, or whether it is in straight tubes, as shown in Figures 4 and 5, so long as the coaxial relationship of the two inductances covers a sufficient distance either side of their respective center points to give the mutual inductance the required stability. If the mutual inductance coupling is too short in relation to the total length of the two inductances, the tendency will be toward less mutual inductance and a decreasing degree of stability of the oscillating unit. Should the mutual coaxial relationship be too long with reference to the total length of the inductances, instability would again result and the advantages of this type of mutual coupling lost.

In Figure 5 the inner tube inductance L3 is connected to the plate circuit A rather than to the grid circuit. The outer tube inductance L4 is connected to the grid circuit B. In all other respects the wiring of the circuit of Figure 5 is the same as that of Figure 4, therefore like reference numerals will be applied to similar parts. From the circuits shown in Figures 4 and 5, it will be apparent that the grid circuit portion of the inductance can either be the inside or the outside member of the coaxial inductance. Again the important relationship between the two inductances is the mutual inductance of the two component parts, for equal distances either side of their coinciding center points, the coaxial portions of the inductances being small when considering their total lengths.

We claim:

1. In a composite radio frequency inductance, a conduit having a coiled portion, an insulating sleeve enclosing the conduit, a metal sleeve conduit enclosing the insulating sleeve, and a third conduit having a coiled portion with its central part physically connected to the metal sleeve.

2. In a composite radio frequency inductance, a conduit formed in a coil for carrying radio frequency waves, an insulating sleeve enclosing at least the central portion of the conduit, a second conduit for carrying radio frequency waves and enclosing at least the central portion of the insulating sleeve, and a second coil having its central portion physically connected to the central portion of the second conduit, the first and second coils extending substantially coaxially with each other to equal distances on both sides of the common center point for both coils, the total distance of the coaxial arrangement of the two conduits being less than a major part of their respective total lengths.

3. A mutual inductance comprising two separate inductance means coaxially related for a limited distance next to their respective coinciding center points, the extremities of the two inductances departing from such coaxial relation-

ship, and the coaxial relationship of the two inductances adjacent to their coinciding centers existing to an extent of less than 50% of the total length of each separate inductance means.

4. A composite radio frequency inductance comprising an inductance having at least a partial loop formed therein, an insulating sleeve enclosing the partial loop, a conductor sleeve enclosing the insulating sleeve, and a second inductance having a plurality of loops, the midpoint of the second inductance being physically connected to the midportion of the conductor sleeve.
